United States Patent Office

Des. 206,140
Patented Nov. 1, 1966

206,140

BAR OF SOAP

Phillip Dowe Meeker, Cincinnati, Ohio, assignor to The Procter & Gamble Company, Cincinnati, Ohio, a corporation of Ohio

Filed Mar. 12, 1965, Ser. No. 84,233

Term of patent 14 years

(Cl. D73—1)

Fig. 1

Fig. 2

Fig. 3

Fig. 4

Fig. 5

Fig. 6

FIG. 1 is an end elevational view of a bar of soap showing my new design.

FIG. 2 is a side elevational view of the same.

FIG. 3 is a top plan view of the same.

FIG. 4 is a bottom plan view of the same.

FIG. 5 is a cross sectional view of the same, taken on the line 5—5 of FIG. 3; and

FIG. 6 is a perspective view of the same.

I claim:

The ornamental design for a bar of soap, as shown.
